UNITED STATES PATENT OFFICE.

BRICE P. SWYERS, OF PITTSBURGH, PENNSYLVANIA, ASSIGNOR TO MOTORS LOCK COMPANY OF AMERICA, OF PITTSBURGH, PENNSYLVANIA, A CORPORATION OF DELAWARE.

LOCK-SWITCH.

1,244,660.

Specification of Letters Patent. Patented Oct. 30, 1917.

Application filed September 25, 1915. Serial No. 52,557.

To all whom it may concern:

Be it known that I, BRICE PHANDERS SWYERS, a citizen of the United States, and a resident of Pittsburgh, in the county of Allegheny and State of Pennsylvania, have invented a new and useful Improvement in Lock-Switches; and I do hereby declare the following to be a full, clear, and exact description thereof.

10 My invention pertains to electric lock-switches, and relates particularly to lock-switches for use in connection with automobiles, to prevent unauthorized running of the engine or tampering with the same. It is the principal object of my invention to improve upon switches of this nature. It is another object of my invention to provide a lock-switch, of the permutation type, which will be of a simple and compact construction and easy to manufacture, and which will render it impossible to complete the circuits necessary for running the engine without previous knowledge of the combination. Other and further objects of my 25 invention will appear from the following description taken in connection with the accompanying drawings.

I have described, by way of example, in the following specification, and shown in the 30 accompanying drawings, one form of lock-switch constructed in accordance with my invention. I wish it understood, however, that the invention may be embodied in other forms, and that changes may be made in the 35 form which is described and shown, without exceeding the scope of the invention, as defined in the appended claims.

In the drawings:

Figure 1 is a diagram illustrating the 40 functions performed by the lock-switch which is described herein;

Fig. 2 is a side elevation of a lock-switch constructed in accordance with my invention, the outer casing being broken away;

Fig. 3 is a section taken on the line 3—3 of Fig. 2, looking in the direction of the arrows;

Fig. 4 is a plan of the lock-switch;

Fig. 5 is a circuit diagram, also showing 50 face views of the contacts employed in the switch;

Figs. 6 and 7 are a side elevation and an inverted plan, respectively, of the top hub and the contact carried thereby; and

Figs. 8 and 9 are similar views of the bottom and the contacts carried thereby.

Like reference characters refer to like parts throughout the following specification and the several figures of the accompanying drawings.

Referring now to Fig. 1, 10 designates the coil of the battery circuit in the ignition system of an automobile, and

11 designates a conductor for connecting the coil 10 with a terminal 13 on the switch. 15 The switch also has a terminal 14 to which is connected the grounding wire 15 of the magneto 16, and has a terminal 17, to which is connected, by a wire 18, one terminal of the battery 19, the other terminal of the 20 battery being grounded. The switch is provided with another terminal, 20, which is connected, by a conductor 21, with electrically operated hood-locks 22, 22, having operating switches 23, 23 in the circuits 25 thereof. A ground connection 24 is established, preferably through the casing of the switch.

The functions performed by the lock-switch to be described below are as follows: 30 A switch-lever is provided which is capable of assuming three positions. In the first position, the terminal 17 is placed in connection with the terminal 13, thereby permitting the engine to be started on the battery. In the center position, the connection is broken between the terminals 17 and 13, and connection is established between the magneto grounding wire 15 and the ground connection 24. In this second position of 35 the switch, the magneto is grounded and the battery is cut off. In the third position of the switch-lever the connection is broken between the terminals 13 and 17, and is also broken between the magneto grounding wire 40 15 and the ground connection 24. In this last position of the switch-lever the engine can be run on the magneto. In all three positions of the switch-lever, a connection is established between the terminals 17 and 100 20, thereby furnishing current to permit of either hood-lock 22 being operated by means of its switch 23. The above connections are only made when the lock is set to its proper combination. The lock is provided with three contact arms, each of which is separately movable and must be set to the right position before the proper connections 105

can be made by means of the switch arm referred to above. When any one of the contact arms is out of its correct position, connection is broken between the terminals 17 and 20, thereby rendering it impossible to operate the hood-locks; connection is broken between the terminals 17 and 23, thereby preventing the engine from being run on battery; and connection established between the magneto grounding wire 15 and the ground connection 24, thereby preventing the engine from being run on the magneto, since the latter is grounded.

Referring now particularly to Figs. 2 to 5, the lock-switch comprises three insulating disks 25, 26 and 27 placed one above the other, the disks being held in spaced relation by means of three metallic standards 28. The disks are surrounded by a casing 29, which is closed at the top by a glass 30. Mounted on the top of the disk 25 is a dial 31. Rotatably mounted in the disk 27 is a spindle 32 having a squared portion 33 upon which is mounted an insulating hub 34. The hub 34 has secured rigidly to the top side thereof, a contact arm 35, and has mounted on the bottom side thereof a contact arm 36. The contact arm 36 is rotatable with respect to the hub within limits 30 which are bounded by a slot 37 therein, through which passes a screw 38. Rotatably mounted on the spindle 32, between the disks 25 and 26, is a hub 39 made of brass or other conducting material. Secured to the lower side of the hub 39 is a contact arm 40. The hub 39 is formed with an upwardly extending boss 41, upon which a metallic switch-lever 42 is mounted so as to be capable of swinging around the boss, such switch-lever extending out through a suitable slot in the casing 29 and having an operating handle on the end thereof. The top part of the boss 41 has a segmental recess cut out therefrom, with which recess 45 engages a segmental clutch-projection 43 formed on the end of a sleeve 44 which extends upwardly through the glass 30 and terminates in a knurled knob 45. The sleeve 44 is slideable upon the spindle 32 and carries a hand 46 which normally lies close to the dial 31, so as to be capable of being brought opposite to any one of a series of indicia which are cut on the dial. To prevent rotation of the sleeve 44 upon the spindle 32, and to limit the sliding movement of the sleeve on the spindle, a pin, 47 is passed through the spindle and engages with its ends in slots 48 formed in the sleeve 44.

In setting the combination of the lock-switch the knob 45 is first turned until the contact arm 40 is in the correct position, which position corresponds with a known index number on the dial 31 to which the hand 46 must point. The knob 45 is then

pulled upwardly, thereby disengaging the clutch-projection 43 from boss 41 of the hub 39 and permitting the spindle to be rotated without affecting the position to which the hub 39 has been brought. The knob 45 is then turned to bring the contact arm 36 into the correct position, which position is indicated by a second number on the dial 31. The knob 45 is then turned in the opposite direction, to bring the contact arm 35 into the correct position, indicated by a third number on the dial, the slot and pin connection between the contact arm 36 and the hub 34 permitting the contact 36 to remain stationary during this last turning movement.

In Fig. 5, of the drawings, the lower side of the disk 27 is shown at A, the upper side of the same disk at B, the lower side of the disk 26 at C, the upper side of the disk 25 at D, and the lower side of the disk 25 at E. The upper side B of the disk 27 carries an outer contact strip 49, such strip being in the form of a circle having a short portion broken out therefrom. At the center of the broken out portion a contact 50 is provided. An arcuate inner contact strip 51 is mounted within the strip 49. One end of the strip 51 terminates on a line with one end of the strip 49; but the other end 95 of the strip 51 terminates some distance short of the other end of the strip 49. Adjacent this last named end of the strip 51, a contact 52 is provided. On the bottom surface C of the disk 26 are mounted outer and inner contact strips 49^a and 51^a, and contacts 50^a and 52^a, similar to the strips 49 and 51 and contacts 50 and 52 referred to above. On the top side D of the disk 26 are mounted outer and inner contact strips 49^b and 51^b, and the contact 50^b, similar to the strips 49 and 51 and the contact 50 referred to above. The contact strips 49, 49^a and 49^b are all connected to ground. The contact strips 51, 51^a and 51^b are all connected with the terminal 14, i. e. with the grounding wire of the magneto. The contact 50 is connected with the terminal 17, i. e. with the battery. The contact 52 is connected with the contact 52^a; and the contact 50^a is connected with the contact 50^b.

On the under side E, of the disk 25 is mounted an arc-shaped contact 53, a part of which is up-set to permit the switch-lever 42, to engage the under side of the same 120 such contact being connected with the terminal 20, i. e. with the hood-lock circuit. A contact 54, concentric with the contact 53 is also provided, such contact being connected with the terminal 13, i. e. with the coil 10. The ends of the contacts 53 and 54 are disposed adjacent to each other, and are inclined, so that a portion of the switch-lever 42 will still rest on the contact 53 when the switch-lever is swung over to engage 130

the contact 54. A metallic plate 55 is mounted on the bottom surface E of the disk 25, so as to be engaged by a contact 56 which passes through the switch-lever 42 and is insulated therefrom. The contact plate 55 is long enough to engage the contact 56 when the switch-lever 42 is in its center position and in its right hand position, and is connected with the frame of the lock switch and consequently to a ground. On the top face C of the disk 26 is mounted a spring contact 57 which engages the switch-lever contact 56 when the switch is in its center position, the spring contact 57 being connected with the grounding wire of the magneto.

The contact arms, 35, 36 and 40 are all of the same shape. Each includes a pair of front fingers adapted to bridge across the inner and outer contact strips except when the arms are set to the correct position, and a rear finger adapted to engage with the contact strip. Fig. 5 of the drawings shows, in dotted lines, each of the contact arms in the correct position, and the switch-lever 42 in its center position. In this condition of the parts, the battery circuit is established from the terminal 17 to the contact 50, from the contact 50 through the arm 36 to the contact 52, from the contact 52 to the contact 52^a, from the contact 52^a through the arm 35 to the contact 50^a, from the contact 50^a to the contact 50^b, from the contact 50^b through the arm 40 and hub 39 to the switch-lever 42, from the switch-lever 42 to the contact 53, and thence to the hood lock circuit. In this condition of the parts, also, the grounding wire of the magneto is connected, through the contact 57 and switch-lever contact 56 with the grounded contact plate 55. With the parts as shown, therefore, the hood lock circuit is alive, the magneto is grounded, and the battery circuit is broken. When the switch-lever 42 is swung to the left, the connections are the same as described above, except that the switch-lever is brought into engagement with the contact 54, which completes the battery circuit to the coil 10 in the same way as the circuit to the hood lock is completed through the contact 53. Moreover, the switch-lever having been moved away from the contact 57, the magneto is no longer grounded. In this condition of the parts, therefore, the battery circuit to the hood lock and to the coil 10 is completed and the grounding connection of the magneto is broken. When the switch-lever 42 is swung to the right, the connections are the same as when the switch-lever is in its center position, except that, the switch-lever having been moved away from the contact 57, the magneto is not grounded. In the left-hand position of the switch-lever, therefore, the engine can be run on battery, and in the right hand

position it can be run on magneto. In the center position of the switch-lever the ignition circuit is totally inoperative. In all positions of the switch-lever, connection is established to the hood-lock circuit.

The above connections can only be made when the contact arms 35, 36 and 40 are set to their proper positions in accordance with the combination of the lock switch. When any one of the contact arms is out of its correct position, such arm will bridge across the inner and outer contact strips. For instance, if the arm 40 is out of its correct position, it will bridge across the strips 49^b and 51^b, thereby effecting a connection between the grounding wire of the magneto and the ground circuit. Likewise, when any one of the contact arms is out of its correct position, say the contact arm 40, it will break the battery circuit to the hood locks 85 and to the coil 10, since such arm will then not be in engagement with the contact 50^b. It will be understood from the above, therefore, that the magneto will be grounded, the battery circuit to the coil will be broken, 90 and the battery circuit to the hood locks will be broken, except when all three of the contact arms are in their correct positions, to which positions they can not be brought without knowledge of the three numbers of 95 the combination of the lock-switch.

In the use of the lock switch described above, when the car is left standing, the knob 45 is turned so as to break the combination. In these circumstances, the car 100 can not possibly be started, since the battery circuit is broken and the magneto is grounded. Moreover, the hood can not be raised to permit of tampering with the engine, since the hood-lock circuit is not energized and consequently the locks can not be operated by closing their respective switches 23. The car is, therefore, completely safeguarded against theft or unauthorized running. When the car is to be 110 started again, it is merely necessary to reset the combination of the lock switch, whereupon the proper ignition circuit can be completed by means of the switch-lever 42.

It will be seen from the above that the lock switch of my invention is of an exceedingly simple construction, and combines all the necessary parts in one device. The lock-switch takes up no more room on the car than does the ordinary three-way 120 switch now in common use; and the construction is such that it is impossible for anyone, either by listening or otherwise, to find out the combination of the switch. The device does away with the necessity of carrying keys, all that is necessary being to recollect the three numbers of the combination.

While I have described in the foregoing specification, a form of my improved lock 130

switch, as applied to a very usual form of automobile ignition circuit, it may be applied to other circuits, what I claim being:

1. In a lock-switch a rotatable shaft, a contact fixedly associated with said shaft, a second contact having a lost-motion connection with said shaft, a second shaft concentric with said first-named shaft and rotatable therewith, a contact mounted to rotate with respect to said first-named shaft, and a clutch between said second named shaft and said rotatable contact.
2. In a lock-switch a shaft having a contact fixedly associated therewith, a second contact rotatable with respect thereto, a bushing slidably mounted on said shaft and rotatable therewith, and a clutch connection between said bushing and said rotatable contact.
3. In a lock-switch a shaft, a contact fixedly associated with said shaft, a second contact having lost-motion connection with said shaft, a contact rotatable with respect to said shaft, a bushing slidably mounted on said shaft and rotatable therewith, and a clutch connection between said bushing and said rotatable contact.
4. In a lock-switch, a frame, a dial carried by said frame, a shaft rotatable in said frame, a contact fixedly associated with said shaft, a contact rotatable with respect to said shaft, a bushing slidably mounted on said shaft and rotatable therewith, a hand carried by said bushing and located adjacent said dial, and a clutch connection between said bushing and said rotatable contact.
5. In a lock-switch, a frame, a dial carried by said frame, a shaft rotatably mounted on said frame, a contact fixedly associated with said shaft, a second contact having a lost-motion connection with said shaft, a contact rotatably mounted on said shaft,

a bushing slidably mounted on said shaft and rotatable therewith, a hand carried by said bushing and located adjacent said dial, and a clutch connection between said bushing and said rotatable contact.

6. In a lock-switch a base member, fixed contacts on said base member, an intermediate member, fixed contacts carried by the lower side of said intermediate member, fixed contacts carried by the upper side of said intermediate member, a shaft mounted to rotate with respect to said members, a contact carried by said base member, a second contact carried by said shaft and co-operating with the fixed contact on the lower side of said intermediate member, one of said contacts being fixedly associated with said shaft and the other of said contacts having a lost-motion connection with said shaft, a contact rotatably mounted on said shaft to co-operate with the fixed contacts on the upper side of said intermediate member, a bushing slidably mounted on said shaft and rotatable therewith, and a clutch connection between said bushing and said rotatable contact.

7. In a lock-switch, a shaft having a contact fixedly associated therewith, a second contact having a lost motion connection with said shaft, a second shaft concentric with said first-named shaft and rotatable therewith, a bushing slidably mounted on said shaft and rotatable therewith, and a clutch connection between said bushing and said rotatable contact.

In testimony whereof, I the said BRICE PIANDERS SWYERS, have hereunto set my hand.

BRICE P. SWYERS.
